US00D991170S

(12) **United States Design Patent** (10) Patent No.: **US D991,170 S**
Tanaka et al. (45) Date of Patent: ** Jul. 4, 2023

(54) **WIRELESS POWER TRANSMITTER**

(71) Applicant: **Panasonic Corporation**, Osaka (JP)

(72) Inventors: **Yohei Tanaka**, Kanagawa Ken (JP);
Ryosuke Hasaba, Kanagawa Ken (JP);
Yuki Tanaka, Tokyo To (JP); **Hiroyuki Tani**, Hyogo Ken (JP)

(73) Assignee: **PANASONIC HOLDINGS CORPORATION**, Osaka (JP)

(**) Term: **15 Years**

(21) Appl. No.: **29/821,908**

(22) Filed: **Jan. 4, 2022**

(30) **Foreign Application Priority Data**

Jul. 6, 2021 (JP) ..... 2021-014644 D

(51) LOC (14) Cl. **13-02**

(52) U.S. Cl.

USPC **D13/108**

(57) **CLAIM**

The ornamental design for a wireless power transmitter, as shown and described.

DESCRIPTION

FIG. 1 is a front perspective view of a wireless power transmitter, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The broken lines in the drawings illustrate portions of the wireless power transmitter which form no part of the claimed design.

1 Claim, 8 Drawing Sheets
